UNITED STATES PATENT OFFICE.

JOHN A. SCOTT, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

BILLIARD-CUE RACK.

1,174,185.

Specification of Letters Patent. Patented Mar. 7, 1916.

Application filed November 8, 1915. Serial No. 60,187.

To all whom it may concern:

Be it known that I, JOHN A. SCOTT, a citizen of the United States, residing at Muskegon, in the county of Muskegon and State 5 of Michigan, have invented certain new and useful Improvements in Billiard-Cue Racks, of which the following is a specification.

This invention relates to billiard cue racks and has for its object the provision of means 10 whereby cues are securely held in upright position in the rack and may be removed from and replaced in the rack with a minimum of effort and without liability of injuring the cues.

15 Other objects and advantages of my invention will be apparent as it is better understood by reference to the following specification when read in connection with the accompanying drawing disclosing a preferred 20 embodiment thereof in which—

Figure 1 illustrates in perspective a cue rack embodying my invention; Fig. 2 is a horizontal section through a portion of the cue-retaining member; Fig. 3 is a side elevation 25 illustrating a portion of the cue-retaining member, the end caps being omitted, and Fig. 4 is a view in perspective of the U-shaped spring and the rollers carried thereby.

30 Referring to the drawings, 1 indicates a frame to which is secured a base 2 provided with a plurality of sockets 3 adapted to receive the butts of the cues. Secured to the frame 1 adjacent the upper end and extending transversely thereof is a cue retaining 35 member 4 provided with a plurality of recesses 5 in its outer edge, the recesses 5 being in alinement with the sockets 3 and being adapted to receive the upper ends of the 40 cues.

A channel 6 is formed in the member 4 surrounding each of the recesses 5 and in each of the channels 6 a U-shaped spring 7 is secured by means of a screw 8. The free 45 ends of the springs 7 are provided with yokes 8', preferably formed integrally therewith, and rollers 9 are journaled in suitable bearings in the yokes 8', the rollers 9 being thus disposed adjacent the mouths of the re-

cesses 5 and the opposed faces of the rollers 50 9 being spaced a distance less than the diameter of the cues adjacent their upper ends. Caps 10 are secured in any suitable manner to the edge of the member 4 to cover the ends of the channels 6.

55 The mode of operation of my improved cue rack should be apparent without further description of the structure thereof. The butts of the cues are disposed in the sockets 3 and the upper ends thereof are pushed inwardly in the corresponding recesses 5 past the rollers 9. The resilient ends of the springs 7 allow the cues to be pushed between the rollers 9, the rollers operating to materially decrease the resistance encountered. 60 The removal of the cues is accomplished in the same manner, the operation 65 being merely reversed.

It will be readily understood from the foregoing that I have perfected a cue rack 70 which allows the cues to be removed from or placed in the rack with a minimum of effort and that the liability of bending or breaking the cues during the operation is entirely overcome while the cues, when disposed in 75 the rack, will be maintained in substantially upright position and can not be accidentally released therefrom.

It will be obvious that various changes 80 may be made in the form, construction, and arrangement of the parts without departing from the spirit and scope of the invention or sacrificing any of its material advantages, the form hereinbefore described being merely a preferred embodiment thereof. 85

I claim:

1. In a rack for billiard cues, a member having a recess in one edge thereof to receive the cue, a channel in said member surrounding said recess, a U-shaped spring disposed 90 in said channel, and rollers supported by said spring in opposite spaced relation adjacent the mouth of said recess, the distance between the opposed faces of said rollers being less than the diameter of the cue. 95

2. In a rack for billiard cues, a member having a plurality of spaced recesses along one edge thereof to receive the cues, a chan-

nel in said member surrounding each of said recesses, a U-shaped spring secured in each of said channels and provided with integral yokes at the free ends thereof, and rollers supported in opposite spaced relation by said yokes adjacent the mouth of said recesses, the distance between the opposed

faces of said rollers being less than the diameter of the cues.

JOHN A. SCOTT.

Witnesses:

F. J. LOEWE,
J. O. MATTESON.
